US00D961562S

(12) **United States Design Patent** (10) **Patent No.:** **US D961,562 S**
(45) **Date of Patent:** **** Aug. 23, 2022**

(54) **TERMINAL FOR NETWORKS**

(71) Applicant: **SAMSUNG ELECTRONICS CO., LTD.**, Suwon-si (KR)

(72) Inventors: **Jihee Kwak**, Suwon-si (KR); **Moonjung Jang**, Suwon-si (KR); **Hyungjun Koo**, Suwon-si (KR)

(73) Assignee: **SAMSUNG ELECTRONICS CO., LTD.**, Gyeonggi-Do (KR)

(**) Term: **15 Years**

(21) Appl. No.: **29/737,437**

(22) Filed: **Jun. 9, 2020**

(30) **Foreign Application Priority Data**

Mar. 2, 2020 (KR) 30-2020-0009362

(51) **LOC (13) Cl.** **14-03**

(52) **U.S. Cl.**

USPC **D14/240**

(58) **Field of Classification Search**

USPC D14/167, 188, 240, 348; D13/110, 184

See application file for complete search history.

(57) **CLAIM**

The ornamental design for a terminal for networks, as shown and described.

DESCRIPTION

FIG. 1 is a front perspective view of a terminal for networks, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

(Continued)

The broken lines illustrating portions of the terminal for networks form no part of the claimed design.
